UNITED STATES PATENT OFFICE.

LEWIS FRITZ, OF CHICAGO, ILLINOIS.

RIFLE.

Application filed August 28, 1922. Serial No. 584,813.

To all whom it may concern:

Be it known that I, LEWIS FRITZ, a citizen of the United States, and a resident of the city of Chicago, county of Cook, and State of Illinois, have invented certain new and useful Improvements in Rifles, of which the following is a specification.

My invention relates to novel improvements in rifles and has for its principal object the provision of an improved construction of this character which will be highly efficient in use.

Among the salient objects of the invention is the provision of utilizing the stock of the rifle for the purpose of storing ammunition which can be readily obtained when wanted.

Other objects will appear hereinafter.

The invention consists in the combinations and arrangements of parts hereinafter described and claimed.

The invention will be best understood by reference to the accompanying drawings forming a part of this specification, and in which,

Fig. 1, is a fragmentary side elevational view of a rifle, embodying the invention;

Fig. 2, is a sectional detail view of the same, taken substantially on line 2—2 of Fig. 1;

Fig. 3, is a fragmentary sectional detail view, of the same, taken substantially as line 3—3 of Fig. 1; and

Fig. 4, is a fragmentary sectional detail view, of the same, taken substantially as line 4—4 of Fig. 1.

Referring to the drawing, (A) indicates a rifle of suitable construction, (B) the stock of the same, and (C) the shoulder rest formed of suitable material.

Formed in the stock (B) is a longitudinally arranged storage compartment or pocket 5, into which the cartridges 6 are stored, the compartment 5 being of a width a trifle larger than the diameter of the cartridges stored therein, preferably in the position shown in Fig. 1. The storage compartment 5 is provided with an entrance opening 7 through which the cartridges pass, said entrance opening being formed in the side of the stock and closed by a sliding door 8, mounted to slide in suitable guides 9 formed on a plate 10, fixed to the stock B by suitable screw members 11, said door being provided with an operating knob 12 projecting through a slot 13 formed in plate 10. The

slidable door 8 is prevented from accidental movement through the medium of a leaf spring 14 engaging the inner surface thereof and mounted in a recess 15 as shown in Fig. 3.

The outer portion, or rather the portion of the storage compartment adjacent the entrance opening 7, is curved in the manner illustrated in Fig. 2, the purposes of which being such that when the cartridges are forced toward the entrance opening 7 through a spring controlled plate 16, the cartridges will ride on the curved surface 17 guiding the same toward the entrance opening 7, where they are received, one at a time into the palm of the hand, when the sliding door is in open position.

While I have provided a spring controlled plate 16 for the purpose of moving the cartridges toward the entrance opening it is to be understood that this provision may be dispensed with, if desired, and when such is the case, by tilting the barrel of the gun upwardly, the cartridges 6 will be caused to roll toward the entrance opening 7.

By the provision of a storage compartment for ammunition as herein described, a number of cartridges can be carried within the stock of the gun and thereby dispensing with the necessity of carrying extra ammunition in a belt or the like.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A rifle including a stock having a storage compartment formed therein and an entrance opening formed in the side of the stock with a curved portion leading to the compartment, a closure member for said opening, and a spring for retaining said member in closed position.

2. A rifle including a stock having a longitudinally arranged storage compartment formed therein and an entrance opening formed in the side of the stock with a curved

portion leading to the compartment, and a spring controlled door provided with an operating handle for said opening.

3. A rifle including a stock having a longitudinally arranged storage compartment formed therein and an entrance opening formed in the side of the stock leading to the compartment, a closure member for the opening, and a member adapted for slidable movement within the compartment for abutment with the adjacent cartridge in the compartment adapted to move the cartridges toward the opening.

4. A rifle including a stock having a longitudinally arranged storage compartment formed therein for the storage of cartridges

and an entrance opening formed in the side of the stock leading to the compartment, a closure member for said opening, and a spring controlled member adapted for slidable movement within the compartment for abutment with the adjacent cartridge in the compartment adapted to move the cartridges toward the opening. 20

In testimony whereof I have signed my 25 name to this specification in the presence of two subscribing witnesses.

LEWIS FRITZ.
